Primary Examiner — Karen E Kearney

CLAIM

(57) The ornamental design for a computing device display screen with computer-generated user interface, as shown and described.

DESCRIPTION

The FIGURE is a front view of a computing device display screen with computer-generated user interface showing our new design.

The broken lines shown in the drawing are for the purpose of illustrating a display screen of a computing device, text, a finger, and other images, and form no part of the claimed design.
